[57] CLAIM

The ornamental design for a combined soap holder and paper towel dispenser, as shown and described.

DESCRIPTION

FIG. 1 is a side elevational view of a combined soap holder and paper towel dispenser showing my new design;

FIG. 2 is a top plan view thereof;

FIG. 3 is a perspective view thereof.

The rear, bottom, and side which are not shown are flat and unornamented.

Fig. 3
